UNITED STATES PATENT OFFICE.

WILLIAM A. RINGLER, OF PHILADELPHIA, PENNSYLVANIA, ASSIGNOR TO THE GLOBE-WERNICKE CO., A CORPORATION OF OHIO.

RECORD-SHEET HOLDER AND SHEETS THEREFOR.

Application filed May 12, 1924. Serial No. 712,602.

My present invention comprehends a novel construction of a sheet-holder, and a novel construction of sheets which can be readily assembled with respect to said holder. The sheet holder is adapted to be secured in a binder of the post or ring type, and it is provided with sheet-securing means whereby both sides of the sheet-holder can be utilized to carry the sheets.

10 It further comprehends a novel construction of a sheet-holder having folds or flaps to retain the sheets in position and provided with means to secure the folds in their folded position.

15 It further comprehends a novel construction of a sheet having a fold or flap at one end which is secured to the body portion of the sheet by means of a fastening device which latter serves to space the sheets from each other when assembled so that the upper or title-receiving portion of all the sheets will be visible.

The sheets can be of different widths without affecting the visibility of the record 25 sheets.

Other novel features of construction and advantage will hereinafter more clearly appear in the detailed description and the appended claims.

30 For the purpose of illustrating the invention, I have shown in the accompanying drawing a typical embodiment of it, which, in practice, will give reliable and satisfactory results. It is however to be understood that this embodiment is typical only and that the 35 various instrumentalities of which my invention consists can be variously arranged and organized, and that the invention is not limited to the precise arrangement and organization of these instrumentalities as herein set forth.

Figure 1 represents a top plan view of a sheet holder and sheets embodying my invention.

45 Figure 2 represents a section on line 2—2 of Figure 1, for the sake of clarity in illustration, only two sheets, one at each side of the holder, being shown.

Figure 3 represents a top plan view of 50 assembled sheets.

Figure 4 represents a top plan view of a portion of the sheet-holder with the sheet-locking elements in their open position.

Figure 5 represents a view similar to Figure 4 but showing the sheet-securing elements 55 in their folded position.

Figure 6 represents a section on line 6—6 of Figure 1.

Similar numerals of reference indicate corresponding parts.

Referring to the drawings:—

1 designates a record sheet holder embodying my invention. The sheet-holder 1 includes a sheet or leaf 2 having spaced apertures 3 in order to adapt it to be assembled in a loose leaf binder of the usual type, such as for example, a binder which is of the ring type or one which is provided with posts adapted to pass through the apertures 3.

The sheet holder further includes a sheet 4 which is secured by adhesive or other means to the sheet 2 and at opposite edge portions it is provided with aligning and securing means for the record sheets. This also reinforces the sheet 2. At each of its opposite ends the sheet 4 is provided with a fold or flap 5 and a narrower fold or locking flap 6, which is turned inwardly towards the attached sheets 2 and 4 and which extends reversely to the wider flap 5, to form within the 75 pocket or channel formed by the latter, a shallower pocket or channel which opens in the opposite direction.

When these flaps 5 and 6 are in their folded position the record sheets 7 are secured in 85 aligned position. These record sheets are preferably of the same length, but, if desired, they may be of variable width as is shown, for example, by the arrows in Figure 3. Each sheet 7 has one of its marginal edge portions 90 bent over to form a locking flap 8, and this flap is secured to the body portion of the sheet by means of a fastening device 9 which may be of any desired character and which as illustrated is shown as a conventional 95 type securing clip or fastener. It will be noted that the locking flap 8 has a straight edge and is of equal width entirely across the end of the record sheet 7, and that the fastener 9 is substantially spaced away from 100 the free edge of the locking flap 8, to leave a free margin of considerable width, the fastener 9 being shown (Fig. 3) as nearer to the line of fold of the flap than to the free edge, so that when a record sheet 7 is mounted 105 in the holder, the free marginal edge portion

of the flap 8 will interlock with the locking flap 6 of the sheet holder, as best shown in Figure 2.

- When two or more record sheets are assembled with their flaps nested one within another, the fastening devices 9 have the function of spacing devices so that the upper marginal or title-receiving portion 10 of each sheet is visible, as shown in Figures 1 and 3.
- 10 In order to secure the fold 5 and the locking flap 6 in their closed position, as shown in Figures 1 and 2, I provide the U-shaped clips 11 which are pivoted at 12 to the sheets 2 and 4. One flange of the U-shaped clip is provided with an inwardly deflected or indented portion 13 forming a rounded projection which is adapted releasably to interlock with a recess or aperture 14 in the fold 5.

In order that the fold 5 and flap 6 can be readily folded into their locking position, the weakened lines 15 may be provided, see Figure 4.

It will be apparent that in my present construction, record sheets can be assembled on both sides of the record-holding sheet or leaf 1. The oppositely disposed clips 11 are moved outwardly, and the fold 5 and the locking flap 6 are unfolded or moved into their open position. The record sheets 7 are assembled as shown in Figure 3 and the folds or flaps 8 are substantially the same width or slightly less width than the width of the fold 5, so that the record sheets 7 will be accurately aligned when the locking flap 6 of the record-sheet holder or support is folded under them as clearly shown in Figure 2. The clips 11 are then moved inwardly into their locking position, and their locking portions 13 interlock with the recesses or apertures 14.

40 Any record sheet can be readily removed or reinserted, the locking clips being first unlocked and the locking flap 6 raised. They can also be adjusted towards the top or bottom of the record-sheet holder 1, as may be desired.

It will be apparent from the foregoing that my present invention can be economically manufactured as the sheets 2 and 4 can be of any desired material, such as for example 50 cardboard or press board, and the clips 11 can be cheaply and economically blanked out from sheet stock.

It is obvious that various modifications may be made in the construction shown in the 55 drawings and above particularly described, within the principle and scope of the invention as defined in the appended claims.

Having thus described my invention what I claim as new and desire to secure by Letters Patent, is:

1. A plurality of record sheets, each consisting of a sheet of material having at one end a fold extending transversely of the sheet, and a securing clip for each sheet to retain 65 its fold against the juxtaposed portion of its

sheet and to determine the amount of visibility of its sheet whereby when the sheets are assembled by nesting their folds one within the other the top edge of the fold of one sheet will have its relative lateral adjustment with the sheet above it limited in one direction by the clip of said sheet above it and thus determine the visibility of the sheet above it. 70

2. A record sheet holder, comprising a sheet of material having folds, record sheets folded at one end, and fastening devices to secure said record-sheet folds to the body portion of their record sheets, said fastening devices serving as spacing elements for assembled record sheets to cause their upper portions to be visible, one of said record-sheet-holder folds being adapted to be folded under said record-sheet folds to secure them in aligned position with each other. 75

3. A device for holding record sheets comprising a supporting sheet having a free margin thereof provided with a series of openings for loose leaf binding purposes, and means carried by the supporting sheet for holding record sheets on both sides of the supporting sheet, said means comprising an inwardly extending outer flap overlying the outer margin of the supporting sheet at one side thereof, an inner locking flap of less width than the said outer flap carried thereby to extend in a reverse direction thereunder, releasable securing means for maintaining both of said flaps in sheet-holding position, another outer flap overlying the other side of the supporting sheet and extending away from the said free margin thereof towards its outer margin, an inner locking flap of less width than the latter flap carried thereby to underlie the said latter flap and extend in a reverse direction thereto, and releasable securing means for maintaining the latter flap and the locking flap carried thereby in sheet-holding position. 85 90 95 100 105

4. The invention defined in claim 3, in which said releasable securing means comprise clips carried by and movably mounted on said supporting sheet to have releasable clamping engagement with said outer flaps. 110

5. A record sheet folded over entirely across one of its end margins to provide a locking flap extending transversely from edge to edge of the sheet, and a fastening device securing said flap in its folded condition and sufficiently spaced from the free edge thereof to provide thereon a locking margin of substantial width, whereby a plurality of such record sheets may be assembled in a series with their folded margins in successive closely nested relation and said fasteners will serve as stops to limit the relative movement 120 of the sheets so that they will overlap with a visible margin exposed on each record sheet and the said free margins of the flaps of the assembled sheets between the free edges of these flaps and said fasteners may be utilized 130

for supporting the assembled series of sheets on a suitable sheet-holding device.

6. A record device comprising a sheet, a holding flap on one side of said sheet extending away from a margin thereof to overlie the sheet, a locking flap extending from the holding flap in an opposite direction to underlie the latter and of less width, another holding flap on the other side of said sheet 10 extending away from the opposite margin of the sheet to overlie the latter, a locking flap extending from the holding flap in an opposite direction to underlie the latter and of less width, and, mounted on each side of said sheet, a series of overlapping record sheets having their adjacent end margins folded over to provide nested locking flaps thereon which are engaged by and interlocked with a holding flap and a locking flap 20 on the said sheet.

7. A holding device for record sheets including a holder sheet having each of two of its opposite margins folded over the sheet in opposite directions to form a holding flap on 25 each of its opposite sides and having the free margin of each of said holding flaps folded under to form a locking flap of less width than the holding flap.

8. The invention defined in claim 7, in combination with a supporting sheet to which said holder sheet is secured and which has a free margin for binding purposes projecting beyond the holder sheet.

9. The invention defined in claim 7, in combination with releasable clips for clamping the opposite ends of each of the holding flaps and locking flaps in their folded sheet-holding position.

10. A record device comprising a holder sheet having each of two of its opposite margins folded over the sheet in opposite directions to form a holding flap on each of its opposite sides and having the free margin of each of said holding flaps folded under to 40 form a locking flap of less width than the holding flap, a supporting sheet to which said holder sheet is secured and which has a free margin for binding purposes projecting beyond the holder sheet, two series of overlapping record sheets of which one such series 45 is carried at each side of the holder sheet with adjacent end margins of the record sheets folded over to provide nested locking flaps thereon which for each such series are

engaged by and interlocked with a holding flap and a locking flap of the holder sheet, and releasable clips for clamping the opposite ends of each of the holding flaps and locking flaps in their folded sheet-holding position. 55 60

11. A holding device for record sheets comprising a supporting sheet, a holder sheet secured on one side of the supporting sheet and extending inwardly from the outer edge of the latter and terminating so as to leave a free inner margin on the supporting sheet which margin is provided with a series of openings for loose leaf binding purposes, a holding flap formed on the outer margin of the holder sheet to fold over the outer margin of the supporting sheet, a locking flap formed on the free margin of the holding flap to fold under the latter, another holding flap formed on the inner margin of the holder sheet to fold over the latter, a locking flap 70 75 formed on and to fold under the free margin of the latter holding flap, and a plurality of releasable clips pivoted on said sheets for clamping the opposite ends of each of the holding flaps and locking flaps in their folded sheet-holding position. 80

12. The invention defined in claim 11, in combination with a series of overlapped record sheets adjacent end margins of which are provided with folded-over nested locking flaps which are releasably engaged by and interlocked with one of said holding flaps and the locking flap carried thereby, a similar series of like record sheets likewise releasably held by the other said holding flap and its locking flap, and for each of said record sheets a fastening device securing its locking flap in folded condition to serve as a stop for limiting the extent of overlap of the sheets of the series and positioned to leave a free margin of said locking flap of sufficient width to be engaged by the locking flap carried by one of said holding flaps provided on the holder sheet. 85 90 95

13. A record sheet having a rectilinear edge at one end the margin of which is folded over to form a locking flap of equal width entirely across that end of the sheet, and a fastening device securing the flap in its folded condition located adjacent one end of the flap and nearer to the line of fold of said flap than to its free edge. 100 105
